LUGGAGE HANDLE OR THE LIKE

Simon Javkin, Brooklyn, N.Y., assignor to The Rotuba
Extruders, Inc., Brooklyn, N.Y., a corporation of New York

Filed Apr. 2, 1964, Ser. No. 79,306

Term of patent 14 years

(Cl. D87—2)

FIG.4

FIG. 1 is a front perspective view of a luggage handle or the like showing my new design;

FIG. 2 is a rear perspective view thereof;

FIG. 3 is a side elevational view thereof; and,

FIG. 4 is a fragmentary cross-sectional view taken on line 4-4 of FIG. 1.

An article of luggage is shown fragmentarily in broken lines in FIGS. 1, 2 and 3 for illustrative purposes only.

I claim:

The ornamental design for a luggage handle or the like, as shown and described.
